William H. Park. Monroe, Michigan. Feb. of. Michigan
(Patented February 25, 1830)

The subscriber referred to in his last letter and making part of the same, containing a description in the words of the law, William Park himself of his improvement in the instrument for determining the variation of the needle, the true meridian and the apparent line.

Be it known that William H. Park of Monroe, Monroe County, State of Michigan, has made an improvement, being an instrument for determining the variation of the needle, the true meridian, and the apparent line, which is described as follows: referenced being had to the engraved drawing of the same making part of this specification. This instrument is supposed to be attached to a circumferential, or some similar instrument having a level in it. There is (a) a graduated to half degrees and works in a clamp (b) with a line (g) and relates the arc (b) to the latitude of the place and is secured by the clamp screw (c), which is also graduated to half degrees. Upon the arc (b) is fixed a movable limb (d) having an opening (e) for a mirror, which limb turns on the center (d) and moves parallel on the arc (b). Upon the movable limb (d) is fixed an arc (f) for bringing the arm off to the sun & moon's declination. Upon the movable limb (d) is also fixed the support (g) upon which rests the arm off bearing the convex lens (h) for converging the rays of the sun, and throwing, and throwing the lens upon the plate (k), which is marked with three lines, and upon the middle one of which, the true meridian is shown. There is also a dark glass (l) placed over the convex lens. Operation. First place the instrument level, locate the arc (b) to the latitude of the place and clamp it, adjust the arm (f) to the sun or moon's declination, and also clamp it, move the limb (d) to the hour of the day, marked on the limb (b) which will throw the sun's image upon the plate.

2.

(b) and which brought upon the centre line, will show the true meridian. The difference between this and that shown to the needle, will be the variation, and the meridian in the (c) will show the apparent line, or that I claim as my invention, is the before described instrument for showing the variation of the needle, by giving the true meridian, or the apparent line.
